ABSTRACT

The present invention relates to a plum tree, *Prunus salicina*, and more particularly to a new and distinct variety broadly characterized by a medium size, vigorous, hardy, and productive tree. Being self-unfruitful, the present variety requires cross pollination from an apricot, interspecific, or plum that blooms during the mid season, such as 'Plumred III' interspecific tree (U.S. Plant Pat. No. 20,864). The present variety produces a heavy amount of flowers that produce an abundance of pollen to entice good bee activity to facilitate pollination. The fruit matures under the ecological conditions described during early to mid July, with first picking on Jul. 10, 2020. The fruit is medium to large in size, dark red with fine freckling throughout in skin appearance, entirely dark red in flesh color, clingstone in type, globose to oblate in shape, firm in texture, juicy, very sweet, and excellent in flavor.

1 Drawing Sheet

1

Botanical classification: *Prunus salicina*.

Varietal denomination: 'PLUMRED XIII'.

BACKGROUND OF THE VARIETY

In a continuing effort to improve the quality of shipping fruits, we, the inventors, typically hybridize a large number of peach, nectarine, plum, apricot, and cherry seedlings each year. We also grow a lesser number of open pollinated seeds of each of these fruits. The present invention relates to a new and distinct variety of plum tree which has been denominated varietally as 'PLUMRED XIII'.

During a typical blooming season we isolate as seed parents both individual and groups of different plum and interspecific trees by covering them with screen houses. A hive of bees is placed inside each such house, and bouquets to provide pollen from different plum, apricot, and interspecific hybrid trees are placed in buckets near the trees approximately every two days for the duration of the bloom. During 2008 one such house containing 'Plumsweet IV' interspecific tree (U.S. Plant Pat. No. 16,461) was crossed by us in this manner. To pollinate this interspecific tree, we selected bouquets from several sources of plum trees without keeping specific written details. Upon reaching maturity the fruit from this interspecific tree was harvested, and the seeds were removed, cracked, stratified and germinated as a group with the label "H24". They were grown as seedlings on their own root in our greenhouse and upon reaching dormancy transplanted to a cultivated area of our experimental orchard located near Le Grand, Calif. in Merced County (San Joaquin Valley). During the summer of 2012

2

the claimed variety was selected by us as a single plant from the group of seedlings described above. Subsequent to origination of the present variety of plum tree, we asexually reproduced it by budding and grafting in the experimental orchard described above, and such reproduction of plant and fruit characteristics were true to the original tree in all respects. The reproduction of the variety included the use of 'Nemaguard' (unpatented) rootstock upon which the present variety was compatible and true to type.

10 The present variety is similar to its seed parent 'Plumsweet IV' interspecific tree (U.S. Plant Pat. No. 16,461), by being self-unfruitful and by producing fruit that is firm and very sweet, but is quite distinguished therefrom by producing fruit that is full red instead of a mottled yellow and red 15 two-tone in skin color, that is much darker red in flesh color, and that ripens about forty-five days earlier.

20 The present variety is most similar to 'Plumred VII' interspecific tree (U.S. Plant Pat. No. 23,688), by being self-unfruitful and by producing fruit that is fairly globose in shape, dark red in its primary skin color, completely red in flesh color, firm in texture, juicy, very sweet, excellent in flavor, and clingstone in type, but is distinguished therefrom by producing fruit that is somewhat larger in size, that has only a moderate amount of very fine freckling instead of a 25 heavy amount of greenish yellow colored freckling in the skin appearance, and that matures about ten days earlier.

SUMMARY OF VARIETY

30 The present plum variety is characterized by a medium size, vigorous, hardy, and fairly productive tree. Being

self-unfruitful, the present variety requires cross pollination from an apricot, interspecific, or plum that blooms during the mid season, such as 'Plumred III' interspecific tree (U.S. Plant Pat. No. 20,864). The present variety produces a heavy amount of flowers that produce an abundance of pollen to entice good bee activity to facilitate pollination. The fruit matures under the ecological conditions described during early to mid July, with first picking on Jul. 10, 2020. The fruit is medium to large in size, dark red with fine freckling throughout in skin appearance, entirely dark red in flesh color, clingstone in type, globose to oblate in shape, firm in texture, juicy, very sweet, and excellent in flavor.

DRAWING

The accompanying photograph consists of four whole fruits positioned to display the characteristics of the skin color and form, one divided fruit to reveal the flesh and stone, a tip shoot growth, typical leaves, and two insets depicting the flower buds and blossoms as they appeared on the tree during the blooming season.

POMOLOGICAL CHARACTERISTICS

Referring now more specifically to the pomological characteristics of this new and distinct variety of plum tree, the following has been observed under the ecological conditions prevailing near Le Grand, Merced County (San Joaquin Valley), Calif. The fruit description was developed at the state of shipping ripe on Jul. 10, 2020, on the original tree during its twelfth growing season. The flower and bud descriptions were developed during the previous blooming season. All major color code designations are by reference to the Inter-Society Color Council, National Bureau of Standards. Common color names are also used occasionally.

PARENTAGE

Seed parent: Plumsweet IV (U.S. Plant Pat. No. 16,461) 40 interspecific tree.

Pollen parent: Unknown plum.

TREE

Size: Medium, reaching and maintaining a height of 10' [3.05 m.] and a spread of 7' [2.13 m.] after twelve growing seasons utilizing typical dormant pruning.

Vigor: Vigorous, responding typically to irrigation and fertilization. The variety grows about 4' [1.22 m.] of surplus top-growth during the spring and summer. The plant should be grown on a standard commercial rootstock for production purposes.

Growth: Upright and dense.

Form: Pruned to a vase form.

Hardiness: Hardy with respect to central California winters.

Heat tolerance: Observed to perform adequately in typical central California climatic conditions, which typically include extended periods of heat.

Drought tolerance: Variety is developed for commercial orchards and requires regular irrigation.

Production: Productive, thinning usually necessary.

Fertility: Self-unfruitful, requiring cross pollination by a suitable early seasonal blooming apricot, interspecific, or plum, such as 'Plumred III' interspecific tree (U.S. Plant Pat. No. 20,864).

Bearing: A fairly consistent bearer, weather dependent, has observed to be light following a rainy bloom season.

Trunk:

Size.—Medium, reaching a maximum diameter of 4 1/4" [107.95 mm.] after the twelfth growing season.

Texture.—Medium to shaggy.

Bark color.—A Grayish brown [61. gy.Br] and Moderate brown [58. m.Br] variegation with Dark brown [59. d.Br] crevices present.

Lenticels.—Approximate Number Per Square Inch: 8.

Color: Moderate yellowish brown [77. m.yBr]. Average Size: 1/4" [6.4 mm.] in length. The width is typically one fourth as much as the length. Shape: Elongated.

Branches:

Size.—Medium, scaffold diameter is 2 1/2" [63.5 mm.] measured 12" above the crotch, limb diameter is 1" [25.4 mm.] measured 12" above the first fork.

Texture.—Medium on first and second year wood, increasing roughness with age.

Color.—1st Year Wood Topside: Grayish red [19. gy.R].

1st Year Wood Underside: Strong yellow green [116. brill.YG]. Older Wood: A Grayish brown [61. gy.Br] and Moderate brown [58. m.Br] variegation with Strong brown [55. s.Br] crevices present.

Lenticels.—Number Per Square Inch: About 20 on second year wood. Color: Deep yellowish brown [75. deep yBr]. Average Size: Medium, 1/16" [1.6 mm.] in length. The width is typically one fourth as much as the length. Shape: Elongated.

Leaves:

Size.—Medium to large. Average Length: 5" [127.0 mm.]. Average Width: 2 1/4" [57.2 mm.].

Arrangement.—Alternate.

Thickness.—Medium.

Form.—Elliptical.

Apex.—Acuminate.

Base.—Acute with an average base angle of 75 degrees.

Surface.—Smooth.

Color.—Dorsal Surface: Moderate olive green [125. m.OlG]. Ventral Surface: Moderate yellow green [120. m.YG].

Margin.—Finely serrate.

Venation.—Pinnately net veined.

Petiole.—Average Length: 11/16" [17.5 mm.]. Average Thickness: 1/16" [1.6 mm.]. Color: Pale yellow green [121. p.YG].

Stipules.—Number: Mostly 2 per leaf, up to 6 per growing tip. Average Length: 1/4" [6.4 mm.]. Color: Light yellow green [119. 1.YG] becoming Light brown [57. 1.Br] with age.

Glands.—Number: Mostly 2 per leaf. Position: Alternate, positioned at the intersection of the petiole and base of leaf blade. Form: Globose. Size: Medium, 1/32" [0.8 mm.] in diameter. Color: Strong yellow green [117. s.YG] becoming Moderate reddish brown [43. m.rBr] in the center with age. Leaf buds: Pointed.

Flower buds:

Hardiness.—Hardy, with respect to central California blooming season.

Diameter.—Typically 3/16" [4.8 mm.] 1 week before bloom.

<i>Length</i> .—Typically $\frac{3}{8}$ " [9.5 mm.] 1 week before bloom.	Suture: A shallow trough extending from the base to near the apex.	
<i>Form</i> .—Free, not touching.	Ventral surface: Rounded, lipped on both sides.	
<i>Surface</i> .—Slightly pubescent.	Lips: Fairly equal.	
<i>Tip color</i> .—White [263. White].	5 Cavity: Flaring.	
Flowers: Perfect, complete, perigynous, usually a single pistil, about thirty stamens, five sepals and petal locations alternately positioned.	<i>Depth</i> .— $\frac{1}{2}$ " [12.7 mm.].	
<i>Average flower diameter</i> .— $1\frac{3}{16}$ " [30.2 mm.].	<i>Breadth</i> .— $1\frac{1}{16}$ " [27.0 mm.].	
<i>Average flower depth</i> .— $\frac{3}{8}$ " [9.5 mm.] when fully open.	Base: Truncate, slightly cordate if viewed parallel to the suture.	
<i>Number of petals</i> .—Five, no double blossoms observed.	10 Apex: Rounded.	
<i>Petal shape</i> .—Oval to very widely obovate.	Pistil point: An inconspicuous Grayish greenish yellow [105. gy.gY] dot, somewhat depressed within the suture.	
<i>Petal margin</i> .—Entire, somewhat wavy.	Stem: Medium.	
<i>Petal arrangement</i> .—Not overlapping.	15 <i>Average length</i> .— $\frac{1}{2}$ " [12.7 mm.].	
<i>Average petal diameter</i> .— $\frac{1}{2}$ " [12.7 mm.].	<i>Average width</i> .— $\frac{9}{32}$ " [2.4 mm.].	
<i>Average petal length</i> .— $\frac{9}{16}$ " [14.3 mm.].	Skin:	
<i>Petal apex</i> .—Rounded.	<i>Thickness</i> .—Medium.	
<i>Petal base</i> .—Slightly acute.	<i>Surface</i> .—Smooth.	
<i>Petal color</i> .—White [263. White] on both sides.	20 <i>Tenacity</i> .—Tenacious to the flesh.	
<i>Anther color</i> .—Moderate yellow [87. m.Y].	<i>Astringency</i> .—Moderate.	
<i>Pollen production</i> .—Strong, enticing to bees.	<i>Tendency to crack</i> .—None observed.	
<i>Stigma color</i> .—Brilliant greenish yellow [98. brill.gY].	25 <i>Color</i> .—Deep purplish red [256. deep pR] smoothly blending into Deep red [13. deep R] with very fine Grayish greenish yellow [105. gy.gY] freckling throughout.	
<i>Stigma position</i> .—Located slightly above the average anther position.	Flesh:	
<i>Stamen position</i> .—Typically located about $\frac{1}{32}$ " [0.8 mm] below the petals.	<i>Color</i> .—Very deep red [14. v.deep R] throughout.	
<i>Sepal color</i> .—Brilliant yellow green [116. brill.YG] on the outside, Light yellow green [119. l.YG] on the inside.	<i>Surface of pit cavity</i> .—Covered with Very deep purplish red [257. v.deep pR] fibers when twisted from the stone.	
<i>Sepal outer surface</i> .—Slightly pubescent.	30 <i>Amygdalin</i> .—Moderate.	
<i>Sepal length</i> .— $\frac{3}{16}$ " [4.8 mm.].	<i>Juice</i> .—Abundant, rich.	
<i>Sepal width</i> .— $\frac{1}{8}$ " [3.2 mm.].	<i>Texture</i> .—Firm, crisp.	
<i>Sepal apex</i> .—Rounded to elliptical to match the width and length.	35 <i>Fibers</i> .—Fine.	
<i>Sepal margin</i> .—Fairly smooth.	<i>Ripens</i> .—Fairly even.	
<i>Average pistil length</i> .— $\frac{3}{4}$ " [19.1 mm.].	<i>Flavor</i> .—A tasty blend of acid in the skin with sweet flesh, typically 21 brix.	
<i>Average stamen length</i> .— $\frac{9}{16}$ " [14.3 mm.].	40 <i>Aroma</i> .—Very slight.	
<i>Ovary</i> .—Smooth.	<i>Eating quality</i> .—Excellent.	
<i>Fragrance</i> .—Moderate.		
<i>Pollen production</i> .—Strong, bee enticing.		
<i>Bloom density</i> .—Moderate.		
<i>Number per cluster</i> .—2 to 5, mostly 2.		
<i>Blooming period</i> .—Medium, about three days before 'Santa Rosa' plum (unpatented).		
	STONE	
	45 Type: Clingstone.	
	<i>Onset of bloom</i> .—One percent on Feb. 19, 2020.	Form: Oval.
	<i>Date of full bloom</i> .—Mar. 2, 2020.	Hilum: Narrow.
	<i>Duration of bloom</i> .—One to two weeks, dependent on ambient temperature.	Base: Rounded.
		Apex: Acute.
		50 Tip: Sharp, about $\frac{1}{8}$ " [3.2 mm.] in length.
		Sides: Fairly equal.
		Surface: Fairly smooth with rounded ridges toward the base.
		External color of stone: Brownish orange [54. brO].
		Pit wall color when cracked: Light yellowish brown [76. lyBr].
		55 Cavity surface color: Moderate yellowish brown [77. m.yBr].
		Average pit wall thickness: $\frac{1}{8}$ " [3.2 mm.].
		Average length: $\frac{7}{8}$ " [22.2 mm.].
		60 Average width: $\frac{5}{8}$ " [15.9 mm.].
		Average breadth: $\frac{3}{8}$ " [9.5 mm.].
		Tendency to split: None observed.
		Kernel:
		<i>Form</i> .—Oval.
		65 <i>Skin color</i> .—Strong yellowish brown [74. s.yBr].
		<i>Pellicle color</i> .—Dark yellowish brown [78. d.yBr].

FRUIT

Maturity when described: Shipping ripe, Jul. 10, 2020.

Date of first picking: Jul. 10, 2020.

Date of last picking: Jul. 30, 2020.

Size: Uniform, medium to large.

Average diameter axially.— $2\frac{5}{8}$ " [66.7 mm.].

Average diameter across cheek plane.— $2\frac{3}{4}$ " [69.9 mm.].

Average diameter across suture plane.— $2\frac{3}{4}$ " [69.9 mm.].

Typical weight.—6.7 ounces [190 grams].

Form: Uniform, globose to oblate, symmetrical.

Longitudinal section form.—Round to somewhat oblate.

Axial view form.—Round.

Vein color.—Deep yellowish brown [75. deep yBr].
Taste.—Bitter.
Viable.—Yes.
Average length.—½" [12.7 mm.].
Average width.—¾" [9.5 mm.].
Amygdalin.—Moderate.

USE

Market: Fresh market and long distance shipping.
 Keeping quality: Good, fruit quality observed to remain in
     good condition after 21 days in standard cold room at 36°
     Fahrenheit [2° Celsius].
 Shipping quality: Good.
 Resistance to insects: No unusual susceptibilities noted.
 Resistance to diseases: No unusual susceptibilities noted.

OTHER NOTES

Although the new variety of plum tree possesses the
 described characteristics under the ecological conditions at 20

Le Grand, Calif., in the central part of the San Joaquin Valley, it is to be expected that variations in these characteristics may occur when farmed in areas with different climatic conditions, different soil types, and/or varying 5 cultural practices.

We claim:

1. A new and distinct variety of plum tree, *Prunus salicina*, substantially as illustrated and described, that is 10 most similar to 'Plumred VII' interspecific tree (U.S. Plant Pat. No. 23,688), by being self-unfruitful and by producing fruit that is fairly globose in shape, dark red in its primary skin color, completely red in flesh color, firm in texture, juicy, very sweet, excellent in flavor, and clingstone in type, 15 but is distinguished therefrom by producing fruit that is somewhat larger in size, that has only a moderate amount of very fine freckling instead of a heavy amount of greenish yellow colored freckling in the skin appearance, and that matures about ten days earlier.
